UNITED STATES PATENT OFFICE.

ASA B. SEGUR, OF OAK PARK, ILLINOIS, ASSIGNOR TO TITE-PACK FILLER COMPANY, OF CHICAGO, ILLINOIS.

EGG-CASE FILLER AND METHOD OF MAKING FILLER.

Application filed February 4, 1924. Serial No. 690,403.

My invention relates to egg case fillers, an object of my present invention being to provide a new and improved filler.

One of the features of my invention is an improved filler construction in which the strips making up the filler are more positively locked together when the filler is open ready for use, and also more positively locked when the filler is collapsed or folded up, so as to prevent fanning and separation thereof.

Another feature of my invention is an improved construction of the filler whereby the breakage of eggs is reduced, that is, a flange construction which reduces the shock from sudden stoppage of the box in shipping.

Another feature of my invention is an improved method of assembling the strips for the egg case filler where a positive locking arrangement is used.

I also show herein an improved machine for carrying out in one way my improved method of process for making fillers, which is directed more particularly to the provision of mechanism which separates or displaces the strips during assembly so as to permit the use of a positive lock construction. This machine is the subject of a copending application, Serial Number 690,404; filed Feb. 4, 1924.

For a better understanding of my invention, reference is to be had to the accompanying drawings, in which—

Fig. 1 is a perspective view of the preferred form of egg case filler of my invention;

Fig. 2 is a detail view of the transverse strip;

Fig. 3 is a detail view of the intermediate longitudinal strips, the outside longitudinal strips differing from this in being flanged as indicated in Fig. 1;

Figs. 4, 5 and 6 show various steps during the assembling operations of the filler;

Fig. 7 shows a portion of a filler in the egg crate detailing more particularly the new shock absorbing construction;

Fig. 8 is an end view of Fig. 7, showing a portion of the longitudinal strip and the end of one of the transverse strips;

Fig. 9 is a view similar to Fig. 7, but showing how the improved construction

takes up the shock from the sudden stoppage;

Fig. 10 shows a modified form of flanged longitudinal strip cooperative with the modified form of assembly strip of Fig. 11 to provide a more positive double hook locking arrangement for the outside or flanged strips;

Fig. 12 is a sectional view through a portion of the filler making machine;

Fig. 13 is a view of a portion of Fig. 10, showing an operation of the flipper arm during the assembling of the filler;

Fig. 14 shows the operation of the flipper for assisting in the ejection of the assembled filler; and

Fig. 15 is a left face view of Fig. 10 with the punch and knife removed and portions broken away to more clearly illustrate the assembling mechanism.

Referring now more in detail first to the egg case filler, as shown in Figs. 1 to 9, and the method of making the same, I provide longitudinal and transverse strips A and B, as shown in Figs. 3 and 2, which strips are assembled to provide the usual cellular egg case filler. In the most desirable form of my invention, as shown in Fig. 1, I provide outer flanged strips A' and A² which are cut for assembling the same as strips A, but have the added feature of the flange formed and assembled to cooperate with the transverse strips B to act as a shock absorber to reduce the breakage of the eggs.

Now the difficulty heretofore has been in assembling the strips when provided with such a positive locking construction.

To overcome this I displace or shift laterally portions of the strips during assembling so as to clear the locking hooks and permit pressing the parts together.

In the preferred form of locking construction used I provide first of all slotted portions in the two strips, which allow displacement of the strips and permit complete pressing together and locking thereof. In the one set of strips, as for example, longitudinal strips A, I provide aligned slots 15—16, preferably simply wide enough to clear the thickness of the other strips, and aligned component slots 17—18 in the other strips, as the transverse or assembly strips B. The outer ends of the slots, as 15 and 17,

have angular openings at 19 and 20, respectively, so as to provide a more ready registration and assembling of the strips as they are pressed toward each other, as indicated in Fig. 4. In order to lock the strips together a hook or nose portion 21 is provided, which is adapted to enter the slot 16 and hook under the hook-stop or edge 22 when the strips are pressed together, as shown in 10 Fig. 6.

The slots 15 and 16 are provided with lateral extensions at their inside ends. This results in a great deal less tearing at the ends of the slots during the assembling operation and seems to facilitate the operation of assembling.

It will be apparent that if it were attempted to simply push the two strips A and B together while retained in their flat position, as indicated in Fig. 4, the paper would simply crumple up or the hook 21 flatten or bend out of shape so that it would not enter slot 16 and lock. This might be avoided by providing plenty of clearance around all the hooks, as indicated at 18' of the central slot so that the wall section 23 between slots 15 and 16 would bend around the hook 21. But this would not provide a most effective lock or prevent fanning and separation of the 30 strips.

Heretofore in the assembling of partitions or strips by automatic machine for the purpose of constructing fillers, the assembling to effect interlocking of the parts has depended upon the ability of one set of partitions to bend around a hook or lock portion of the other partitions through a sufficient cutaway clearance to allow them to lock when pressed together. However, in such prior constructions the interengaging slots and hook portions of the strips or partitions have been such that sufficient clearance had to be allowed to permit assembling of the parts without destroying the interengaging hook portions. Also the paper used varies with a variation in humidity, and varies in quality. Furthermore, the shape of the lock varied according to condition of the dies. The assembling of the fillers also differed with a difference in atmospheric conditions as by destroying the locking hooks or noses or interfering with the proper bending of the paper during the assembling. To overcome this difficulty to some extent, the slot and hook constructions heretofore used have been such and provided with such clearance that the partitions would not properly lock with the cell expanded for use, or would permit fanning and disengagement of the strips when collapsed.

To overcome these difficulties I have first of all provided slot constructions, preferably oppositely disposed and of such character that the slots on each strip grip the walls of 65 the opposite strip in a vise-like manner when

the filler is collapsed. This prevents the filler from being fanned out, that is the partitions pulled so as to give a diamond like appearance to the collapsed filler, and therefore practically prevents the filler from being pulled apart during the fanning. This might otherwise occur during the handling or opening of the filler when it is to be placed in the egg case.

As noted from assembly strip B in Fig. 2, 75 the center slot 18' has the clearance around the hook 21 but the other slots are preferably without the clearance so that the strips when assembled are sufficiently held by the straight slots and oppositely disposed hooks 80 to prevent fanning and separation thereof.

As previously stated, if it were attempted to push the two sets of partitions together while held flat or straight, as shown in Fig. 4, the paper would crumple or the hook 21 flatten out or bend over, interfering with assembling of the strips and locking thereof.

In order to properly assemble the strips with such a positive locking and holding slot construction, this may be done by warping 90 or displacing a portion of one strip (B) relative to the other so that the wall adjacent the locking hook of one strip (B) is moved to one side to permit the other strip (A) to be swung on a pivot from its upper end by the 95 hook as it is descending and force its way over the hook into locking engagement by the rotary or pivotal movement of the suspended strip A. The direction of this pivotal movement is indicated by the arrows at bottom of strips A in Figs. 4 and 5.

One method of doing this is illustrated in Figs. 4 to 6. In Fig. 4 the strips are shown with the assembly strip B just about to enter the longitudinal strip A. The downward 105 movement of strip B continues but before the hook 21 engages the bottom of slot 15 of longitudinal strip A, a portion of the assembly strip B is moved to one side to open the slot 18 and clear the hook. This is preferably 110 done shortly after the two strips are in mesh, and in practice in connection with the standard fillers the movement begins when the strips are overlapping approximately three-eighths of an inch. The downward movement of B is of course continuing and the displaced portion of the strip is moved to open the slot and sufficiently clear hook 21 to permit longitudinal strip A to be pushed laterally by the down coming hook 21 until 120 the hook is beneath the hook-stop 22. The strip B then is free to spring back or be forced back into place and the parts are locked as indicated in Fig. 6. In the assembly operation I preferably block the sides 125 of the longitudinal strips at the top so as to suspend them, you might say, and permit a rotation or swinging movement with the pivot point at the top where blocked, and the bottom free to swing sufficiently to per- 130

mit the hook to freely pass the intermediate wall portion 23. By this arrangement I find the added advantage of the slots 15 in the longitudinal strips A also being separated, 5 due to the strip A being held by blocks 38 at its sides along the top edge to the rear of the slot 15, but free on the other side of the slot 15, thereby making the assembly operation easier. In blocking the longitudinal 10 strip so as to permit opening of its slot, this blocking is preferably done only to the rear of the assembly strip as indicated by the elements 38 in Fig. 4, and which will be more particularly pointed out in connection with 15 the machine.

It will be noted from Fig. 2 that the hooks 21 in the slots 18 are oppositely disposed, thus assisting in preventing separation of the strips. With the hooks oppositely disposed 20 I do not find it necessary to warp or move laterally all of the sections intermediate the slots, but only some of them, and that by moving the sections marked X an assembly may be readily accomplished. That 25 is, counting from the left in Fig. 2, the first, third, sixth and eighth sections.

There is another feature to my filler previously referred to, and that is the shock absorbing construction for reducing breakage. 30

Heretofore fillers have been constructed with flanged strips as A¹ and A², but the flanges were so constructed and held as to interfere with a most effective shock absorbing 35 operation. In my improved construction, as more clearly illustrated in Figs. 7 to 9, the transverse strip B is cut away at 24 to clear the flange A', which flange is formed so as to bend beneath the flat or 40 separator 25, as shown in Fig. 7. With the filler in the crate and loaded, as shown in Fig. 7, the crate is positioned for shipping, as in the freight car, with the flange of A' in the direction of movement. 45 Should there be a sudden stoppage, naturally the tendency is to carry the loaded fillers toward the end wall of the crate. The result is that the flange of A' gradually takes up the shock of stopping, bending 50 from point 26 until the corner of the flange abuts the stop 27, as shown in Fig. 9. This flange prevents the tips of the assembly strips B from coming into sudden contact with the walls of the box and crushing 55 them.

In Figs. 10 and 11 I have shown a modified form of lock for use in preferably locking the outer or flanged strips A only. In using this lock, an L-shaped lock-stop is 60 used instead of a T, and a second hook as at 21^a to engage a cooperating slot shown in B of Fig. 11. By the use of this double hook lock, it is more difficult to separate the outer and more exposed flanged strip A 65 from the strips B.

In carrying out my improved method in the manufacture and assembling of the improved filler, I preferably employ a machine as shown in a copending application for cell case machines, Serial Number 584,087, modified so as to make the proper perforations 70 in the strips and assemble them.

In Figs. 12 to 15 I have shown the modified portions of this machine. Generally stated the machine is arranged to cut and assemble strips from continuous rolls of strawboard, using one roll which is slotted and flanged to provide the longitudinal strips A, and a second roll to provide the transverse or assembly strips B. In this 75 machine the sheet is fed between slitting rollers to form longitudinal strips A which are fed forwardly through intermittently operated feed rollers 27 passing between the blades of the shears 28 which are operated 80 to sever the fillers as they are completed. The slots 15-16 are cut in the strips A by suitable punch mechanism and these strips as they are fed along are stopped momentarily as each set of slots 15-16 reaches a 85 position beneath the assembly strip B, so as to permit the assembly strip to be forced down over strips A. The strips B have their slots pierced by the punch 29 as the sheet moves downwardly, the transverse 90 strips being severed by the cooperating knife blades 30-31 constructed from double plates so as to cut a clearance 24 at each end of the transverse strips to receive the flange. The stationary blade 31 extends 95 across the machine and is notched at points 31^a at each strip A, A¹, A², so as to set beneath the tops of strips A whereby the assembly strip is positively severed at a point not above the tops of the strips A. An 100 auxiliary knife 31' has its cutting edge set above the cutting edge of 31 to cooperate with the auxiliary blade 30' of the swinging 105 knife to clear the corners 24 of strips B as stated.

As previously stated, I have provided a positive interlocking construction and in order to assemble the strips preferably transversely move or wrap portions of the strips out of the plane of the sheet, and to this end have provided mechanism including a flipper device C adapted to engage portions of the transverse or assembly strip as it is descending over the longitudinal strips. This flipper 115 C comprises a pivotally mounted shaft 32 having fingers 33, 34, 35 and 36 extending upwardly between or alongside the longitudinal strips A. Normally, when the assembly strip starts to descend, these fingers are back in the position indicated in Fig. 13. As the transverse strip moves downwardly the flipper arms of C are moved forwardly 120 by means of the link mechanism 37 connected to the end of the flipper shaft 32, until these fingers engage and move the por- 125 130

tions X forwardly. These portions X are moved to sufficiently clear the hooks 21 to permit the longitudinal sections A to be swung clear of the hook 21 so that the hook can engage under the locking slot 22. This lateral movement of strips A is a pivotal one, swinging from the point of suspension at the top and to this end blocks 38 are placed alongside each longitudinal strip as indicated at only the center strip A of Fig. 15 and by the dotted lines in Fig. 12. These blocks 38 stop back of the blades of the shears 28, but in order to support the tops of the strips at a point closer to the line of assembly, I provide fingers as 39 which reach over the shears 28 as indicated in Fig. 12. These fingers are not needed at every point but only as indicated in Fig. 13 by the dotted lines of 39. As the two sets of strips are being forced together, the slots in the assembly set are separated by the flipper fingers as stated and also this causes the slots in the other set to separate as already described, permitting an easier assembly of the strips.

In actual practice, and in connection with the regular commercial fillers, I secure a suitable operation by having the flipper fingers start forward with the transverse strip down a quarter of an inch, stop when the strip is down three-eighths of an inch, staying there until the strip is down one and three-eighths of an inch, then starting back and crossing the assembly line as the strip is down one and one-half of an inch. The strips are from two and one-fourth to two and five-sixteenths inches wide. The transverse or assembly strip, of course, continues its movement downwardly until fully assembled and after the hooks 21 snap into the locking slot the strain on the longitudinal strips is released, thereby permitting the portions X of the transverse strip to move back into their normal plane, they having been held over by the longitudinal strips after having been once moved out of alignment by the flipper fingers. During the downward travel of the assembly strip B, the portions intermediate the moved portions X sometimes curl toward the front or back, but in order to keep them in vertical position I provide guides in the form of thin strips 40 and 41 secured to the front and back of the flipper shaft between which the ends enter as the strip moves downwardly to full assembly.

The assembling having been completed, the cutter knives 30—31 cut off the transverse strip and the filler is then moved forward the distance of one cell for the next assembling operation.

During this longitudinal feeding movement after the assembling, due to clogging of the parts or other reasons, the cell sometimes sticks and a free feeding by the rollers 27 is not effected. To assist this feeding and prevent sticking I cause a second opera-

tion of the flipper fingers, as indicated in Fig. 14. That is, during the longitudinal feeding of the filler and before the feed of one section is completed, another operation of the flipper fingers is effected, as indicated in Fig. 14, causing them to strike the transverse strip and drive it forward, should it be stuck or its feeding movement interfered with. The fingers, of course, return to the normal position indicated in Fig. 13 before the next assembling operation.

What I claim as new and desire to secure by United States Letters Patent is:

1. A cellular filler comprising interlocking longitudinal and transverse partition strips to form cells, the locks for said strips being formed of separated transversely aligned straight slots and an intermediate wall portion in one strip, and separated transversely aligned straight slots in the other strip having an intermediate hook portion so as to form a continuous slot of substantially like width throughout its length and said hook being positioned to engage the end of one of the other straight slots to lock the strips when assembled, the said hook containing slots having a lateral extension of the slot at the end thereof.

2. A cellular filler comprising interlocking longitudinal and transverse partition strips to form the cells, the lock construction for said strips being formed of a transverse slot arrangement in the first strip substantially of the thickness of the other strip so as to closely embrace it when assembled and a hook-stop, and a transverse parallel sided slot arrangement in said other strip substantially of the thickness of the first strip so as to closely embrace it when assembled and with a lock hook disposed intermediate of said latter slot disposed to engage the hook-stop, said latter slot continuing around the hook as of a width substantially of the thickness of the engaged strip, each of said lock hook strips including seven slots the outer ones of which have the hooks facing towards the end of the strip, the next two slots from each end having facing hooks, whereby the end portions of the strip beyond the end slots and the portions between the facing hooks are freely laterally movable to clear the hooks for assembling.

3. A cellular filler for a container having rigidly spaced side and end walls, comprising a plurality of superposed fillers separated by flat spacer members, each filler comprising vertically walled cells formed by the interlocking of partitions extending transversely of the container from one side wall to the other and other partitions extending longitudinally of the container and terminating short of both end walls, one of the vertical partitions at each end of the filler being bent upon itself to afford a flange extending below and clear of the flat

spacer and resting upon the longitudinal partitions and projecting beyond the tips of the latter to present a free edge towards the adjacent end container wall, the transverse ⁵ partition to which each of the said flange extensions is adjoined being transversely flexible, each flat spacer member being free of interlock with the fillers spaced thereby and

clear of the two extensions of the next lower ¹⁰ filler causing said extensions to flex the said two partitions to gradually take up the shock of sudden starting or stopping of travel of the container.

In witness whereof, I hereunto subscribe my name this 12th day of January, 1924.

ASA B. SEGUR.
